(57) **CLAIM**

The ornamental design for a wine bottle opener, as shown and described.

DESCRIPTION

FIG. 1 is a front perspective view of a wine bottle opener showing my new design with handles in a closed position.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top plan view thereof.

FIG. 8 is a bottom plan view thereof.

FIG. 9 is a front perspective view thereof with the handles in an open position.

FIG. 10 is a front view thereof with the handles in the open position.

FIG. 11 is a left side view thereof with the handles in the open position; and,

FIG. 12 is a right side view thereof with the handles in the open position.

The broken lines in the drawings depict portions of the wine bottle opener that form no part of the claimed design.

1 Claim, 12 Drawing Sheets
